US0D1101180S

(12) **United States Design Patent** (10) **Patent No.:** **US D1,101,180 S**
(45) **Date of Patent:** **** Nov. 4, 2025**

(54) **SKIN TREATMENT DEVICE**

(71) Applicant: **SHENZHEN ULIKE SMART ELECTRONICS CO., LTD.**, Shenzhen (CN)

(72) Inventor: **Shouwang Luo**, Shenzhen (CN)

(73) Assignee: **SHENZHEN ULIKE SMART ELECTRONICS CO., LTD.**, Guangdong (CN)

(*) Notice: Patent file contains an affidavit/declaration under 37 CFR 1.130(b).

(**) Term: **15 Years**

(21) Appl. No.: **29/969,251**

(22) Filed: **Oct. 22, 2024**

(51) LOC (15) Cl. **24-01**
(52) U.S. Cl. USPC **D24/200**; D24/209; D24/214

(58) **Field of Classification Search**

(57) **CLAIM**

The ornamental design for a skin treatment device as shown and described.

DESCRIPTION

FIG. 1 is a top, front and right perspective view of a skin treatment device showing my new design;

FIG. 2 is a bottom, rear and left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dash-dash broken lines in the drawings depict portions of the skin treatment device handle that form no part of the claim design.

1 Claim, 8 Drawing Sheets
